ATTORNEY

UNITED STATES PATENT OFFICE

MAX RACHLIN, OF BROOKLYN, NEW YORK

GUTTER HANGER

Application filed March 31, 1927, Serial No. 180,035. Renewed May 2, 1928.

The present invention relates to improvements in gutter hangers, and more particularly to that type which is known in the trade as "shank and circle" hanger. A main object of the invention is to provide a simple and inexpensive adjustable hanger the shank and circle portions of which are so formed and combined that rocking of the circle on the shank is effectively prevented. I also aim to so construct and design the circle that it may be made of comparatively thin stock and still be capable of withstanding the strains and stresses to which it is ordinarily subjected. I further aim to provide a bent shank of channel form with reinforcement for the junction of its angularly arranged portions, one of which portions engages the roof, while the other is attached to the circle. As here shown and described, the shank and circle are each stamped from a single piece of sheet metal.

One of the many possible embodiments of the invention is illustrated in the accompanying drawings, in which:

Figure 1 is a side elevation of a gutter hanger constructed in accordance with the present invention, the gutter being shown in position thereon; Fig. 2 is a section taken on line 2-2 of Fig. 1, on a larger scale, the gutter being removed; Fig. 3 is a section taken on line 3-3 of Fig. 1, also on a larger scale; Fig. 4 is a top plan view, on a larger scale, of the outer end of the circle element of the hanger; Fig. 5 is a top plan view of the shank element of the hanger; Fig. 6 is a section taken on line 6-6 of Fig. 5, on a larger scale; and Fig. 7 is a plan view of the blank from which the circle element of the hanger is formed.

As appears from the drawings, the hanger comprises a gutter supporting circle 10 and a shank 11, these elements being adjustably secured together by a screw-bolt 12, the shank being in practice attached to the supporting structure in any suitable manner, for instance by nails, not shown. As shown in Figs. 1 and 3, the heel 26 of the circle 10 is laterally embossed or ridged at 27 for lateral engagement in the channelled shank 11, and also has a lateral shoulder, adjacent the ridge

and the lower edge of the heel, for engagement with the outer face or edge of the shank, this shoulder being formed by the outer side of a groove 29 in the shank. This interengagement of the parts effectively prevents 55 rocking of the one on the other.

The gutter hanger circle 10 is stamped from a single strip 13 of sheet metal, shown straight in Fig. 7 of the drawings. This strip 13 is rolled or bent edgewise into the shape of an arc of a circle to form the gutter hanger circle. The circle comprises a vertical web 14, provided at its outer end with a hook 15, which is adapted to extend through an opening 16 in a hook-shaped element 17, the latter being adapted to be bent over the bead 18 of the gutter 19, as shown in Fig. 1 of the drawings. The upper edge of the vertical web 14 merges into an outwardly bent horizontal portion 20 (Fig. 2), and this portion 20 into an upwardly extending portion 21, which extends in parallel relation to the vertical web. The upwardly extending portion 21 merges into a horizontal flange 22, which forms a gutter seat 22 and overhangs the vertical web 14. The inner end of the gutter seat 22 terminates in a finger or catch 23, for engagement with the plain edge 24 of the gutter 19. As shown in Fig. 2 of the drawings, a groove 25 extends throughout the length of the circle, between the web 14 and the gutter seat 22. The vertical web 14 is disposed centrally in relation to the gutter seat 22, although this is not essential. 75

At its inner end, the circle 10 has a heel portion 26, which is laterally ridged by virtue of having a vertical rib 27 formed in the web 14. As shown in Fig. 3, the rib 27 is formed by bending or embossing the web 14 to a channel section. In the said rib 27 is provided a vertical row of apertures 28, to take the screw-bolt 12. In the heel 26, alongside and paralleling the rib 27, there is a vertical groove 29, formed by a fold of the sheet metal throughout the height of the heel. The upper portion of the groove 29 is in effect a continuation of the groove 25 between the flange 22 and the web 14, while its lower portion represents a bending of the web 14. In other 80 95 100

words, the groove 29 merges laterally with the groove 25.

The shank 11 is also stamped from a single piece of sheet metal. It comprises a vertical stem 30 of channel formation. Throughout practically its whole extent, vertically considered, the stem 30 is apertured, as at 31, so that the circle 10 may be adjusted thereon in a well understood manner. At the upper end 10 of the stem 30 the shank is subjected to a twisting operation, as at 32 and bent, so that the upper portion 33 extends at an angle to the stem. The portion 33 of the shank is also of channel formation. It widens out gradually 15 from the twist 32 to its free end 34, and the height of its vertical webs 35 decreases gradually from the twist 32 to the free end 34. In other words, the portion 33 of the shank is tapered longitudinally and transversely, so 20 that it may be readily inserted beneath the shingles on a roof. As shown in the drawings, nevertheless, the shank has a constant cross-sectional area. The portion 33 of the shank is provided with a row of apertures 36, 25 through which nails may be driven into the roof structure in order to secure the shank thereto. As appears from the drawings, the shank has at the juncture of the stem 30 and the roof engaging portion 33 a longitudinal 30 rib 37, formed by embossment of the bottom of the shank channel in the same general way as in Fig. 3, for the purpose of strengthening the said juncture. Breaking or distorting of the shank at the said juncture is thus effectively 35 prevented.

When the elements 10 and 11 of the hanger are being assembled, the vertical rib 27 of the circle heel is seated in the channel of the stem or shank 30, and one of the vertical webs or 40 flanges 30' of the stem 30 is seated in the vertical groove 29 in the circle heel 26. The lower outer side of the groove 29 (below the groove 25) affords a square shoulder to engage against the outer side of the shank stem 45 30, and rocking of the circle on the shank is thus effectively prevented. As shown in the drawings, the upper and lower portions of the groove 29 are each of a width to fit the web 30' (Figs. 1 and 3).

50 A plurality of shanks and circles, suitably spaced apart, are used for mounting the gutter on the supporting structure. In use, the shanks are first attached to the supporting structure, the circles shifted on the respective 55 shanks to the desired height and screw-bolts 12 put through registering apertures in the shanks and circles. The gutter is then put in place, the hook-shaped element 17 being engaged with the gutter bead. It will be noted that, inasmuch as the circle is bent or 60 rolled edgewise in forming the same, and by virtue of its cross-sectional configuration, the circle may be made of comparatively thin stock and yet be able to withstand the strain 65 and stresses to which it is subjected.

In stamping the circle portion of the hanger, the hook 15 on the outer end of the circle may be united with the gutter seat 22 by a web 38, as shown in Fig. 4 of the drawings, thus providing a very rigid construction 70 at the outer end of the circle which will effectively withstand torsional force.

What I claim is:—

1. A gutter hanger circle stamped from a single strip of sheet metal curved edgewise 75 in an arc of a circle and including a body portion having a flange forming a gutter seat and a groove adjacent said flange, a vertically extending heel portion, and a vertically extending rib bent out from said heel portion, 80 said rib being apertured and said heel portion being provided with a groove extending in parallel relation to said rib throughout the entire length of the latter and disposed between said rib and said flange and merging 85 with said first-mentioned groove.

2. A gutter hanger circle stamped from a single strip of sheet metal curved edgewise in an arc of a circle and including a vertical web extending throughout the length of 90 the circle, an outwardly extending horizontal portion merging with said web, an upwardly extending portion merging with said horizontal portion, and a horizontal flange merging into said upwardly extending portion, 95 said horizontal flange forming a gutter seat.

3. In a gutter hanger according to claim 2, said web being disposed centrally in relation to said flange.

4. In a gutter hanger according to claim 2, 100 at the outer end of said circle said web being connected with said flange by a web extending at right angles to the plane of said vertical web.

5. A gutter hanger shank of channel formation stamped from a single strip of sheet metal and comprising a vertically extending stem apertured substantially throughout its length, a roof attaching portion extending at an angle to said stem, and a rib formed at the 110 juncture of said stem and said roof attaching portion, said rib extending into the channel of both said stem and said roof attaching portion.

6. A gutter hanger circle having a heel 115 portion laterally ridged for lateral engagement in a channelled shank, and provided with a shoulder adjacent the lower edge of the heel to engage against the outer face of the shank and thereby keep the circle from turning downward relative to the shank.

7. A gutter hanger circle having a heel portion laterally ridged for lateral engagement in a channelled shank, and grooved alongside the ridge throughout the height of 120 the heel to take the corresponding shank flange.

8. A gutter hanger circle of sheet metal having a heel portion laterally embossed for lateral engagement in a channelled shank, 130

and folded alongside the embossment throughout the height of the heel to take the corresponding shank flange.

Signed at New York, in the county of New
5 York and State of New York, this 29th day
of March, A. D. 1927.

MAX RACHLIN.
